UNITED STATES PATENT OFFICE.

ADOLPH SATTLER, OF LANGE, TEXAS.

WATER-GAP GATE.

1,072,778.

Specification of Letters Patent.

Patented Sept. 9, 1913.

Application filed October 7, 1912. Serial No. 724,403.

To all whom it may concern:

Be it known that I, ADOLPH SATTLER, a citizen of the United States, residing at Lange, in the county of Gillespie and State 5 of Texas, have invented certain new and useful Improvements in Water-Gap Gates; and I do hereby declare the following to be a full, clear, and exact description of the invention, such as will enable others skilled 10 in the art to which it appertains to make and use the same.

This invention relates to water gap gates, that is to say to gates or fence closures arranged across a stream, creek or ravine and 15 serving as a barrier to prevent cattle or stock from wandering along the stream or gap.

In case of heavy rains or freshets, the force of the water and impact of timber, 20 which often drifts down stream, is apt to wash away the barrier or seriously injure the same, rendering it necessary to reconstruct or repair it and endangering the loss of cattle or stock until this is done.

25 It is the object of this invention to prevent injury to the barrier or gate, thereby saving the trouble and expense of repairs or reconstruction and at the same time removing the danger of cattle or stock escaping 30 when the stream is swollen. To this end the anchorage of the gate, fence or barrier in the bed of the stream or gap will be automatically released by unusual force of water flowing over said bed, and as soon as released, the barrier will be automatically 35 raised to a position at or near the surface of the swollen stream where it is not liable to be struck by drifting timber and yet is in position to prevent the escape of cattle or 40 stock along or within wading distance of the bank.

The invention will be hereinafter first fully described in connection with the accompanying drawings, which form a part of 45 this specification, and then pointed out in the claims at the end of the description.

In the drawings: Figure 1 is a side elevation of a gate or barrier constructed substantially in accordance with this invention, 50 the same being shown as it appears in its normal position looking up stream, and the bed of the stream or gap and portions of both banks thereof being shown in section. Fig. 2 is a plan view of the showing in Fig. 55 1. Fig. 3 is an enlarged detail of the anchoring device in its normal locked posi-

tion. Fig. 4 is a broken vertical section on the line 4—4 of Fig. 1 looking in the direction of the arrow. Fig. 5 is a view taken similarly to Fig. 1 but illustrating the raised 60 position of the gate or barrier, and Fig. 6 is a detail plan view of the anchoring device in its released position.

Referring to the drawings by letters of reference, A and A' designate the banks of 65 a stream or gap, the bed of which is indicated at B. On the left hand bank A, as shown in Figs. 1, 2 and 5, there is mounted an angular frame or derrick C suitably fulcrumed, as at c, and preferably consisting 70 of two lever arms c' and c² extending substantially at right angles to each other and at opposite sides of the fulcrum, a brace or cross-bar c³ and a weight D secured to the end of the lever arm c' at the side of the 75 fulcrum away from the stream. As illustrated, the lever arms and cross-bar or brace may each consist of two bars or members which may be spaced apart in order to provide a better support for the weight and 80 prevent lateral play of the frame.

The bars or members of the lever arm c' are preferably spread well apart from the fulcrum to the end where the weight is attached. The bars or members of the lever c² 85 may converge toward the juncture of said lever and the brace c³, the bars or members of the latter also converging in the same way. The end of the lever arm c² may be supported in normal position upon a standard E located near the edge of the bank. To the end of this lever arm, one end of the 90 gate or barrier F is attached in any suitable manner, as by a loop of wire G. On the other bank A' there is erected another 95 standard E' having a lug or projection e adapted to be engaged by a link h, or its equivalent, attached to the right-hand end of the gate or barrier in any suitable manner as by a loop of wire H. The link h is also 100 connected, preferably by a flexible connection, such as the wire K, with the bank. As shown, this flexible connection K is secured to the top of another standard k in order to support the gate well above the bank when 105 said gate is raised.

The gate or barrier F may consist of a plurality of uprights or posts f and a series of wires f' strung between them. One of the posts is provided on or near its lower 110 end with an eye or loop f² which normally engages or is hooked under an anchoring

pin or lug l projecting in the direction of the current from an anchor plate L fixed in the bed of the stream or gap. While I have shown the gate as having three posts or uprights f , it will be understood that a different number may be employed according to the width of the gap. Where three posts are used, the intermediate one may be provided with the eye or loop f^2 and the other two be arranged respectively at or near the edges of the opposite banks. In case a larger number of posts are required, it may be desirable to anchor more than one of them, which can readily be done by duplicating the anchoring device shown and described in connection with the middle post of the illustrated example of the invention.

The eye or loop f^2 is normally retained in engagement with the anchoring pin by a locking device which is adapted to be automatically actuated to release said eye or loop when the force of the current is increased by heavy rains or freshets to such an extent as to endanger the gate. As illustrated, this locking device consists of a jointed strip M preferably in three sections m , m' and m^2 hinged end to end. The free end of the section m is pivoted to a fixture, the anchor plate for instance, as at N . This fixed pivot is preferably on the upstream side of the gate and in line with the anchoring lug in the direction the current flows. The intermediate section m' of the strip normally extends across the loop or eye on the down-stream side of the gate, and rests upon the protruding end of the anchoring lug, the other section m^2 normally extends up-stream. On the free end of said section m^2 is mounted a wing or plate P presented to the impact of the current which, however, is normally insufficient to dislodge it. When the force of the current is increased by heavy rains or freshets, it acts upon said plate or wing to move the locking device or strip M to the position illustrated in Fig. 6 for releasing the loop or eye. It will be observed that the section m^2 of the locking strip is prevented from being moved to the wrong side of the anchoring lug by a stop R which normally holds said section in a position where it is inclined toward that side of the anchoring pin to which it must swing in order to release the eye or loop.

The operation of the device will be readily understood from the foregoing description taken in conjunction with the drawings. The normal positions of the parts being as shown in Figs. 1, 2 and 3, when the locking device is released by an unusual force of current, as just explained, said current, acting in the direction in which the anchoring lug extends, will push the eye or loop f^2 off of said lug, whereupon the

weighted frame or derrick C will automatically raise the gate or barrier clear of the stream, the upward lift of said gate or barrier disengaging the link h from the projection e so that the flexible connection K is extended, as illustrated in Fig. 5. The length of the arm c^2 of the frame or derrick C , as well as the height of the standard k governs the distance the gate is raised above the banks, and said distance may, therefore, be varied by changing the length of said arm c^2 , the height of said standard k , or both. When the freshet subsides, the gate or barrier may be quickly and easily adjusted again to normal position by depressing the arm c^2 of the frame or derrick, connecting the loop or eye on the intermediate post of the gate to the anchoring pin, adjusting the locking device to the position shown in Figs. 1, 2 and 3 so as to secure said eye or loop on said anchoring pin, and attaching the link h to the projection e .

Having thus described my invention, what I claim as new and desire to secure by Letters Patent is:—

1. The combination with a gate, of means to anchor the same, a pivoted frame having arms extending at an angle to each other and at opposite sides of its fulcrum, one of said arms being connected to one end of the gate and normally arranged in a lowered position, and the other arm being weighted and normally arranged in a raised position, whereby the gate will be automatically raised when released from its anchorage and means for securing the other end of the gate adapted to be automatically disconnected when the gate is raised.

2. The combination with a gate, of means to anchor the same, a pivoted frame having arms extending substantially at right angles to each other and at opposite sides of its fulcrum, one of said arms being connected to the gate and the other arm being weighted, and means to normally support the arm which is attached to the gate in a lowered but slightly inclined position, whereby the weighted arm is inclined to the vertical and is adapted to automatically raise the gate when released from its anchorage.

3. The combination with a water gap gate consisting of a plurality of posts and a series of wires strung between them, of means for detachably anchoring one of the posts down in the bed of the gap, and means for fastening the end posts up on the banks of the gap, whereby the anchored post may rise to the level of the end posts when the former is released from its anchorage.

4. The combination with a gate, of means to anchor the same, a pivoted frame having arms extending at an angle to each other and at opposite sides of its fulcrum, one of said arms being connected to one end of the gate

and the other arm being weighted, means to normally support the arm which is attached to the gate in a lowered but slightly inclined position, whereby the weighted arm is inclined to the vertical and is adapted to automatically raise the gate when released from its anchorage, and means for securing the other end of the gate adapted to be automatically disconnected when the gate is raised.

5 5. The combination with a gate, of means to anchor the same, and a pivoted frame having arms extending substantially at right angles to each other and at opposite sides of its fulcrum, one of said arms being connected to the gate, and the other arm being weighted, whereby said gate will be automatically raised when released from its anchorage, said frame also having a brace connecting its arms, the latter and the brace comprising pairs of bars spaced apart for the purpose specified, the bars of said brace and of the arm which is connected to the gate converging toward their juncture.

20 6. The combination with a gate, of means to anchor the same, means connected to one end of the gate for automatically raising the same when released from its anchorage, and means for securing the other end of the gate, said latter means adapted to be automatically disconnected when the gate is raised.

25 7. The combination with a gate, of means to anchor the same, means connected to one end of the gate for automatically raising the same when released from its anchorage, means for securing the other end of the gate, said latter means adapted to be automatically disconnected when the gate is raised, and a flexible connection between a fixture and the end of the gate having said securing means for the purpose specified.

40 8. The combination with a gate, of means to anchor the same, means connected to one end of the gate for automatically raising the same when released from its anchorage, a vertical fixed lug near the other end of said gate, and a link secured to the gate and adapted to engage said lug when said gate is anchored and be automatically disconnected therefrom when the gate is released from its anchorage.

45 9. The combination with a gate, of means to anchor the same, a vertical fixed lug near one end of said gate, a link secured to the gate and adapted to engage said lug when said gate is anchored, and means for automatically raising the gate, when released from its anchorage, above the level of the top of said lug, whereby said link is automatically disconnected from the lug as the gate is raised.

55 10. The combination with a gate, of means to anchor the same, a vertical fixed lug near one end of said gate, a link secured to the

gate and adapted to engage said lug when said gate is anchored, and means for automatically raising the gate, when released from its anchorage, above the level of the top of said lug, whereby said link is automatically disconnected from the lug as the gate is raised, and a flexible connection between said link and a fixture for supporting said gate in its raised position.

70 11. A water gap gate comprising a series of wires spaced apart with means at each end, and at an intermediate point for holding said wires in separated relation and adapting the gate to span a depression or water gap with its ends elevated and its center lowered, means for securing the lowered intermediate portion of the gate in a fixed position under normal conditions and for holding its ends upright while so secured, and means actuated by the force of an abnormal current for releasing said securing means, together with means for automatically raising the gate when said securing means is released.

75 12. A water gap gate comprising a series of supports having flexible connections there-between, the end supports of the series being adapted to be supported on the banks of the gap, and an intermediate support detachably connected in the bed of the stream, means for automatically releasing said intermediate support, together with means for automatically raising said gate when said intermediate support is released.

80 13. The combination with a water gap gate having a loop, of an anchoring pin adapted to be normally engaged by said loop, and means for normally locking said loop on said pin, said means adapted to be automatically actuated by the current to release the gate when said current becomes strong enough to endanger the gate.

85 100 14. The combination with a water-gap gate having a loop, of an anchoring pin adapted to be normally engaged by said loop, means for normally locking said loop on said pin, said means adapted to be automatically actuated by the current to release the gate when said current becomes strong enough to endanger the gate, and means for automatically raising said gate when said loop is released from said anchoring pin.

90 110 15. The combination with a water gap gate having a loop, of an anchoring pin adapted to be normally engaged by said loop, and means for normally locking said loop on said pin, said means including a plate disposed to receive the impact of the current for automatically releasing said locking means when the current becomes strong enough to endanger the gate.

115 120 125 16. The combination with a water gap gate having a loop, of an anchoring pin adapted to be normally engaged by said loop, means for normally locking said loop on

said pin, said means including a plate disposed to receive the impact of the current for automatically releasing said locking means when the current becomes strong enough to endanger the gate, and means for automatically raising said gate when said loop is released from said anchoring pin.

17. The combination with a water gap gate having a loop, of an anchoring pin extending in the direction of the current and adapted to be normally engaged by said loop, a locking device comprising a sectional jointed strip having one end secured to a fixture on the up-stream side of the gate, said sectional strip normally extending around the loop on the down-stream side of the gate, and a plate carried by said strip and disposed to receive the impact of the current for disengaging said strip from the loop when said current becomes strong enough to endanger the gate.

18. The combination with a water gap gate having a loop, of an anchoring pin extending in the direction of the current and adapted to be normally engaged by said loop, a locking device comprising a sectional jointed strip having one end secured to a fixture on the up-stream side of the gate, said sectional strip normally extending around the loop on the down-stream side of the gate, a plate carried by said strip and disposed to receive the impact of the current for disengaging said strip from the loop when said current becomes strong enough to endanger the gate, and means for automatically raising said gate when said loop is released from said anchoring pin.

19. The combination with a water gap gate having a loop, of an anchoring pin extending in the direction of the current and adapted to be normally engaged by said loop, a locking device comprising a sectional jointed strip having one end secured to a

fixture on the up-stream side of the gate, the intermediate section of said strip normally extending across the loop on the down-stream side of the gate, and the free end section normally extending toward the up-stream side and also being slightly inclined toward the course it must take to release the loop, a stop for normally holding said end-section in the inclined position indicated, and a plate carried by said end-section and disposed to receive the impact of the current for disengaging said strip from said loop when said current becomes sufficiently strong to endanger the gate.

20. The combination with a water gap gate having a loop, of an anchoring pin extending in the direction of the current and adapted to be normally engaged by said loop, a locking device comprising a sectional jointed strip having one end secured to a fixture on the up-stream side of the gate, the intermediate section of said strip normally extending across the loop on the down-stream side of the gate, and the free end section normally extending toward the up-stream side and also being slightly inclined toward the course it must take to release the loop, a stop for normally holding said end-section in the inclined position indicated, a plate carried by said end-section and disposed to receive the impact of the current for disengaging said strip from said loop when said current becomes sufficiently strong to endanger the gate, and means for automatically raising said gate when said loop is released from said anchoring pin.

In testimony whereof I affix my signature in the presence of two witnesses.

ADOLPH SATTLER.
